UNITED STATES PATENT OFFICE

CARROLL J. SHERMAN, OF HOUSTON, TEXAS, ASSIGNOR OF ONE-THIRD TO EWING WERLEIN AND ONE-SIXTH TO CHARLES H. SHERMAN, BOTH OF HARRIS COUNTY, TEXAS

BURNER

Application filed August 15, 1927. Serial No. 212,940.

This invention relates to new and useful improvements in a burner.

One object of the invention is to provide a burner of the character described which has been specially designed for utilizing either oil or gas as a fuel and which is of such construction that the change from one character of fuel to the other may be easily and quickly made.

10 Another object of the invention is to provide a burner of the character described equipped with novel means for supplying air, and mixing it with the fuel, at the point of combustion, thereby securing a proper mixture of the fuel and air.

15 A further feature of the invention is to provide a burner of the character described which is of such construction as to prevent the fuel from entering the air chamber.

20 With the above and other objects in view the invention has particular relation to certain novel features of construction, operation and arrangement of parts, an example of which is given in this specification and illustrated in the accompanying drawings, where-
in:

The figure shows a vertical sectional view of the burner.

25 Referring now more particularly to the drawings the numeral 1 designates the stand which is supported by the legs 2 and which includes an upstanding tube 3 into which the gas supply line 4 is connected. There is a cup shaped support 5 screwed onto the upper end of a tubular nipple 6, which forms part of said supply line and which is connected into the upper end of the T connection 7 incorporated into said line. The support encloses an air chamber 8 which is supplied with air 40 through the inlet 9.

Within the chamber 8 there is a T connection 10 whose lower end is threaded onto the upper end of the nipple 11 and the lower end of this nipple is threaded into the bottom of 45 the support 5, said nipple 11 also forming a continuation of the gas supply line.

50 A tubular anchor 12 has its lower end screwed into the upper end of the T 10 and screwed onto the upper end of this anchor there is an approximately conical shaped gen-

erator 13 having the internal chamber 14 and the generator is provided with an outlet 15 at its apex.

There is an oil line 16 which passes through the air inlet opening 9 and is screwed into the T 10 and anchored to the upper end of the nipple 11 and extending up through the anchor 12 there is a tube 17 whose upper end extends through the opening 15, and terminates slightly above said opening, said tube being spaced from the anchor 12 as well as from the walls of the opening 15.

55 The upper surface of the generator is formed with a plurality of annular grooves 18 spaced apart therearound and its margin is outwardly turned forming an outwardly extending annular flange, 19.

60 There is a generator cap 20 whose upper side is substantially convex and whose under side is formed to conform to the external contour of the top of the generator and this cap is fitted over said generator and is held spaced therefrom by suitable depending spacing legs 21 which rest on the flange 19. The margin of the cap 20 is outwardly turned forming 65 an annular flange 22 which extends out beyond the flange 19 of the generator. The cap is formed with a central upstanding eye 23 provided for convenience in handling said cap.

70 Mounted on the support 5 there is an annular base 24 having the spaced outer and inner upstanding marginal flanges 25 and 26 forming an annular channel 27 between them. Mounted on the outer flange 26, of this base, and detachable therefrom there is an annular 75 upwardly flared combustion ring 28.

80 Mounted on a supporting sleeve 29, which surrounds the anchor 12 and which rests on the T 10 there is an upwardly flared baffle 30, which extends up through the enlarged central opening 31, of the base 24, and is spaced from the walls of said opening and protects the generator 13 against drafts of cool air and deflects said air to the point of combustion.

90 There is a fuel inlet line 32 which is turned upwardly through the support 5 and extends through and terminates above the baffle 30. This line is provided to supply fuel to sustain 95 100

the pilot flame, and this flame is protected against extinguishment by the baffle 30.

In case gas is used it will flow in through the line 4 and be discharged into the space between the generator 13 and its cap 20 and will flow down said space and be discharged in a circular film, or sheet, around the margin of the flange 22 where it will be mingled with the air passing upwardly through the opening 31 and the mixture will be there ignited by the pilot flame.

In case oil is used as a fuel the oil will flow in through the line 16 and pass upwardly filling the chamber 14 and overflowing into the passageway between the generator and generator cap and passing thence to the channel 27 where it may be ignited. When the generator becomes hot the oil in the chamber 14 will be vaporized and will pass thence in vapor form, in an annular film or sheet between the generator and generator cap and will be mingled with the air, as hereinbefore stated, forming a combustible mixture. The flange 19 is extended outwardly so as to carry the liquid fuel out beyond the opening 31 to prevent the drippings from falling back into the air chamber 8.

The lines 4 and 16 may be equipped with conventional control valves (not shown), so that either form of fuel, or both, may be admitted, as desired.

Further embodiments, modifications and variations may be resorted to within the principle of the invention.

35. What I claim is:—

1. A burner including a cup-like support having an air chamber therein, an annular base on said support having a central air passageway, a generator above said base, a generator cap spaced above the generator forming a channel between them, a fuel line terminating in said space, said generator having an outwardly extending annular flange and said cap having an outwardly extended annular flange which extends out, substantially horizontally, beyond the generator flange.

2. A burner including a support having an air chamber therein provided with an air inlet, a base mounted on said support having an air passageway therethrough, a generator disposed above said passageway having an internal chamber, a generator cap above the generator and spaced therefrom to form a channel, there being a passageway leading from said generator chamber into said channel, said generator and cap each having an outwardly extended, horizontally disposed, annular flange and an upwardly flared baffle in said air passageway and spaced from the wall thereof, said baffle surrounding the lower part of the generator.

3. A burner including a support having an air chamber therein provided with an air inlet, an annular base removably mounted

on said support and having an air passageway therethrough, a generator above said base, a generator cap spaced above the generator forming a channel between them which has an annular outlet, means for delivering fuel into said channel, an upwardly flared deflector disposed within and spaced from the walls of said air passageway and arranged to direct the air upwardly and outwardly across said outlet, said generator having an internal chamber and an outlet port leading from said generator chamber into said channel, and means for delivering fuel into said generator chamber.

4. A burner including a cup-like support having an internal air chamber provided with an inlet passageway, an annular base mounted on said support and having a central passageway, said base having inner and outer upstanding marginal flanges, a generator above said base provided with an internal fuel chamber and having an annular, horizontally disposed, outwardly extended flange, a generator cap above and spaced from the generator forming a channel between them, said cap having a horizontally disposed, marginal flange extending outwardly beyond the generator flange, means for delivering fuel directly into said channel, means for delivering fuel into said fuel chamber, said fuel chamber having an outlet port leading into said channel.

5. A burner including a cup-like support having an internal air chamber provided with an inlet passageway, an annular base mounted on said support and having a central passageway, said base having inner and outer upstanding marginal flanges, a generator above said base provided with an internal fuel chamber and having an annular outwardly extended flange, a generator cap above and spaced from the generator forming a channel between them having an annular outlet, said cap having a marginal flange, extending outwardly beyond the generator flange, means for delivering fuel directly into said fuel chamber, said fuel chamber having an outlet port leading into said channel and an upwardly flared deflector disposed in and spaced from the walls of said central passageway and effective to deliver an upwardly and outwardly directed air current transversely of said annular outlet.

6. A fuel burner comprising a liquid fuel conducting tube, a generator on the upper end thereof with an upper overflow opening therein, a generator cap spaced slightly from said generator, means to feed liquid fuel to said tube, a pipe for gaseous fuel extending upwardly through said tube and extending through said overflow opening to a point above said generator, and means to direct a flow of air across the outer margins of said generator and said cap.

7. A fuel burner comprising a liquid fuel

conducting tube, a generator on the upper end thereof with an upper overflow opening therein, a generator cap spaced slightly from said generator, means to feed liquid fuel to said tube, a pipe for gaseous fuel extending upwardly through said tube, the margins of said generator and cap forming a combustion space between them, means to direct a flow of air across said combustion space, and

5 means to ignite said fuel.

10 8. A fuel burner comprising a liquid fuel conducting tube, a generator on the upper end thereof with an upper overflow opening therein, a generator cap spaced slightly from said generator, means to feed liquid fuel to said tube, a pipe for gaseous fuel extending upwardly through said tube, means to direct an upward flow of air beneath said generator, a pilot light beneath said generator, said 15 air directing means being effective to deflect the air away from said light.

9. A fuel burner comprising a generator having a fuel chamber therein, said chamber having an overflow opening at its upper end, 20 means to feed fuel to said chamber, a generator cap shaped to fit over said generator and spaced slightly from said generator to form a narrow fuel channel, a flaring wall about said generator forming a combustion 25 chamber, means to direct air upwardly into said chamber around the lower wall of said generator, a pilot light below said generator, said air directing means being effective to deflect said air away from said light.

30 35 In testimony whereof I have signed my name to this specification.
